UNITED STATES PATENT OFFICE

144,571

DESIGN FOR A GAME BOARD

Emma E. Kloss, Chicago, Ill.

Application September 8, 1945, Serial No. 121,939

Term of patent 14 years

(Cl. D34—5)

To all whom it may concern:

Be it known that I, Emma E. Kloss, a citizen of the United States, residing at Chicago, Cook County, Illinois, have invented a new, original, and ornamental Design for a Game Board, of which the following is a specification, reference being had to the accompanying drawings, forming a part thereof.

Fig. 1 is a face view of one-half of a game board embodying my new design; and

Fig. 2 is a face view of the other half of the board.

The game board consists of a sheet or board of conventional thickness with the design applied to the playing surface of the sheet.

I claim:

The ornamental design for a game board, as shown and described.

EMMA E. KLOSS.
